United States Patent [19]
Avari

US00D334977S

[11] Patent Number: Des. 334,977

[45] Date of Patent: ** Apr. 20, 1993

[54] AIR DIRECTING DEVICE

[75] Inventor: S. R. Avari, Garden City, N.Y.

[73] Assignee: CTS Consolidated Technical Services, Inc., Garden City, N.Y.

[**] Term: 14 Years

[21] Appl. No.: 541,713

[22] Filed: Jun. 21, 1990

[52] U.S. Cl. D23/387

[58] Field of Search D23/387, 388, 389, D25/53, 57, 47; 454/314, 315, 279; 52/473, 78, D12/163

[57] CLAIM

The ornamental design for an air directing device, as shown and described.

DESCRIPTION

FIG. 1 is a top, front and left side perspective view of an air directing device showing my new design;

FIG. 2 is a front elevational view thereof;

FIG. 3 is a right side elevational view thereof, the left side being a mirror image of that shown;

FIG. 4 is a rear elevational view thereof;

FIG. 5 is a top plan view thereof; and,

FIG. 6 is a bottom plan view thereof.

FIG. 1

FIG. 2

FIG. 3

FIG. 5

FIG. 4

FIG. 6
